UNITED STATES PATENT OFFICE.

ANDREW B. FOANS, OF NEW YORK, N. Y.

METHOD AND MOLD FOR MAKING CONCRETE BLOCKS.

Application filed May 16, 1923. Serial No. 639,258.

To all whom it may concern:

Be it known that I, ANDREW B. FOANS, a citizen of the United States, residing at New York, in the county of New York and 5 State of New York, have invented new and useful Improvements in Methods and Molds for Making Concrete Blocks, of which the following is a specification.

This invention relates to a mold and 10 method of making concrete building blocks of the kind in which two spaced sections of the block are connected together by tie rods.

An object of the invention is to provide 15 the block with a continuous air space dividing the sections, and tie rods securely anchored in the concrete so as to firmly hold the spaced sections together.

Another object of the invention is to provide 20 means arranged in the box to slidably coact with the tie rods so that the block can readily be removed after the concrete sets.

Another object of the invention is to provide 25 a simple and efficient method of molding the blocks without the employment of a core member made to form the air space between the parallel sections of concrete.

Another object of the invention is to provide 30 a method of molding the two block sections in which one section is formed, then reversed, and the projecting tie rods inserted into the concrete of a second mold.

The invention resides more particularly 35 in the novel combinations hereinafter described and claimed, reference being made to the accompanying drawing in which:—

Fig. 1 represents a vertical longitudinal section of a mold embodying this invention.

Fig. 2 is a vertical transverse section 40 taken along the line 2—2 of the same.

Fig. 3 is a plan view of the same.

Fig. 4 is a perspective view of a tie rod.

Fig. 5 is a vertical longitudinal section 45 showing the method of making the second section.

Fig. 6 is a vertical transverse section taken along the line 6—6 of Fig. 5.

Fig. 7 is a vertical longitudinal section 50 showing the method of forming a corner block.

Fig. 8 is a perspective view of a block.

In the drawing the numeral 10 designates 55 a mold or box having an open top and provided with pairs of brackets 11 extending inwardly from the sides of the box above

the bottom. The brackets are fixed to the side and each has a bifurcated or slotted end 12 to support a tie rod 14 projecting upwardly. The tie rod is substantially U shaped and the two shanks are turned inwardly at their lower ends to slidably or removably coact with the slots of a pair of the brackets, as indicated in Fig. 3. There are two of the tie rods shown, but it will be understood that any number could be used depending on the size of the block. A removable side 18 attached to the box by hooks 19 or otherwise, permits the withdrawal of the block section after the concrete sets.

The method of forming the block of concrete shown in Fig. 8 includes a trough like box made in any shape to conform to the contour of the concrete block. The tie rods are positioned in the slots 12 and the cement is poured into the box thereby embedding the lower portions of the tie rods in the block, while the upper part projects upward; the section can then be removed from the mold by sliding it out.

The second section is then molded in a box 15 which is filled with concrete and the first section is turned upside down. The air space between the sections is gauged by blocks of wood 17 arranged on top of the box 15 before the projecting ends of the tie rods are inserted into the concrete. After the cement sets in the box 15 the section can be lifted or pulled out of the box with the transverse ends of the rods securely embedded in the block.

The method of forming the corner block shown in Fig. 7 consists in providing a box 20 with an upwardly projecting extension 21 to form the angle to the lower block. An upper box 16 having slots 22 in the bottom is arranged over the lower box. The slots can be covered with paper or other material to prevent leakage of concrete. Both boxes can be provided with removable sides to permit removal of the sections after they set. The slots in the box permit the tie rods to move out with the block section. The slots in the box 16 extend transversely to the edge adjacent to the removable side so that when it is desirable to remove the box from the concrete block all that is necessary is to detach a side, such as 18, in Fig. 3 and slide the box from the block. After the side and block 17 are re-

moved the box can be pushed downward to loosen it from the concrete block and the slots then permit the box to be slid from under the concrete block. The slots glide by the portions of the rods exposed between the two concrete blocks.

I claim:

1. A mold for making concrete blocks comprising a box having an open top, bifurcated brackets secured in the box, and tie rods arranged to movably coat with the brackets projecting upwardly from the box.

2. A mold for making concrete blocks comprising a box having an open top, bifurcated brackets secured in the sides of the box, tie rods arranged to slidingly coat with the brackets projecting upwardly from the box, and a removable side board to open the box so as to slide the block from the box.

20 3. A mold for making concrete blocks comprising a lower box having an open top, bifurcated brackets secured in the lower box, tie rods arranged to slidingly coat with the brackets projecting upwardly from the box, 25 a box mounted above the lower box, and slots located in the upper box made to slidingly engage the projecting tie rods.

4. A mold for making concrete blocks comprising a lower box having an open top, 30 with an upwardly projecting extension, bifurcated brackets secured in the lower box, tie rods arranged to slidingly coat with the brackets projecting upwardly from the box, a box mounted above the lower box, 35 means for gauging the distance of the box above the lower box, and slots in the upper

box made to slidingly engage the projecting tie rods.

5. The method of making two section concrete blocks having a continuous air space 40 with connecting tie rods, which consists in molding one of the sections with portions of the tie rods embedded and projecting therefrom, reversing the section, and molding the second block to embed portions of 45 the projecting tie rods.

6. The method of making concrete blocks with a continuous air space, which consists in providing a box, positioning a number of tie rods in the box so that their ends project therefrom, pouring concrete into the box, removing the block from the box, reversing the block, and inserting the projecting portions of the tie rods into a mass 50 of concrete.

55 7. The method of making concrete blocks with a continuous air space, which consists in providing a box having brackets, mounting a number of tie rods on the brackets so that their ends project therefrom, pouring concrete into the box, removing the block from the box, reversing the block, and inserting the projecting portions of the tie rods into a mass of concrete formed in a box.

60 In testimony whereof I have hereunto set my hand in the presence of two subscribing witnesses.

ANDREW B. FOANS.
